Patented June 21, 1921.

G. I. MITCHELL
Inventor.

UNITED STATES PATENT OFFICE.

GROVER IRA MITCHELL, OF MADISON, WISCONSIN.

FASTENING DEVICE.

1,382,412.

Specification of Letters Patent. Patented June 21, 1921.

Application filed July 1, 1920. Serial No. 393,311.

To all whom it may concern:

Be it known that I, GROVER IRA MITCHELL, a citizen of the United States, residing at Madison, in the county of Dane and State 5 of Wisconsin, (whose post-office address is No. 303 Extension Building, Madison, Wisconsin,) have invented a new and useful Fastening Device, of which the following is a specification.

10 My invention relates to improvements in fastening devices whereby a plural number of plates or pieces provided with an elongated slot are held together by a cross member which is inserted through the slot and 15 then turned to a position at right angles with the slot, said cross member being held against the material being held by the tension of a spring which is part of the fastener, this spring bearing against one side of the 20 material being held while the cross member bears against the other side, the combined action of the spring and of the cross member holding the material firmly together.

The objects of my improvement are, first, 25 to provide a fastener easily installed in position; second, to provide a fastener which can be easily and cheaply manufactured; third, to provide a fastener having ample strength to fulfil the purpose for which it is intended; 30 and, fourth, to provide a fastener which will stay in position, after it has been applied to the material being held, under adverse conditions, such as the jar and vibration of moving vehicles and machinery.

35 I attain these objects by the device illustrated in the accompanying drawing, in which—

Figure 1 is a side view of the complete fastener as it appears when removed from 40 the material being held; Fig. 2 is a view in perspective of the fastener applied to two plates of metal suitably prepared to receive the fastener, part of the coils which form the spring of the fastener being cut away 45 so as to expose the interior construction of the fastener and to show the method of application to the material being held.

Similar numerals and letters refer to similar parts in the two views.

50 The fastener is intended to be formed from spring wire or other suitable material, a cross member being formed in the wire as at 1, the two ends of the wire 2 and 3 are carried away from the cross member 1 to 55 form a central stem composed of the wire

2 and the wire 3. At a suitable distance from the cross member 1 the wire 2 is bent at right angles and coiled into a circular head 4. Just below the head 4, as appears in Fig. 1, the wire 3 is bent at right angles 60 and is coiled into the spring 5 which terminates in the coil 6 in close association with the cross member 1. The lower coil 6 of the spring 5 is so formed as to have the greater 65 part of its circumference in contact with the material being held when the fastener is applied as in Fig. 2.

In order that the fastener will stay in position when applied to the material being held, the lower member or coil 6 of the spring 5 as 70 appears in Fig. 1 has two projections, spaced 180 degrees apart, these projections 7 are so located with reference to the cross member 1 that when the fastener is applied and the cross member 1 has been placed through the 75 slot C, Fig. 2, which pierces the plate A and the plate B, and the device turned to bring the cross member 1 perpendicular to the slot C, the projections 7 will register with the slot C and hold the fastener in position. 80

The fastener is applied to the material to be held by grasping the coiled head 4 in the fingers, inserting the cross member 1 in the slot C, and pushing the cross member 1 through the slot C until the cross member 1 85 can be turned at right angles to the slot C. In order that the user may be able to get a firm grip on the fastener when applying it to the material to be held I have provided the coiled head 4 with a knurled surface, 90 but it is understood that any other suitable means of securing a good grip may be employed within the scope of the claims.

The fastening device herein pictured and described is made of one piece of spring 95 wire. It is understood, however, that this construction is but one of the many ways in which the basic idea of this invention may be applied, and that any other construction embodying one or more pieces of any suitable material forming an operative unit capable of holding several plates or parts together substantially as herein described may be used within the scope of the several claims. 100

Having thus described my invention, what I claim as new and patentable follows:

1. A fastening device comprising a cross member, a central stem, and a spring adapted to exert pressure upon parts interposed 110

between the spring and the cross member, said spring having projections adapted to register with slots in the parts held.

2. A device, for holding together a number of plates provided with slots, comprising a cross member adapted to be put through the slots, said cross member being integral with a central stem, and a coiled spring integral with the central stem adapted to exert pressure upon the plates interposed between the cross member and the spring, one coil of said spring having projections adapted to register with the slots in the plates when the cross member is put through the slots and turned to a position at right angles to the slots.
- 10 3. A fastening device comprising a cross

member integral with a central stem; a head with means of turning the device secured to the central stem; and a spring integral with the central stem, said spring being confined by the head and adapted to exert pressure upon material interposed between the spring and the cross member, one coil of said spring having projections adapted to register with the slot in the material held.

In witness whereof I have hereunto set my signature in the presence of two witnesses on this 24th day of June, A. D. 1920.

GROVER IRA MITCHELL.

Witnesses:

LAWRENCE E. BLAIR,
HERBERT O. BRICKSON.
